DESCRIPTION**FOREIGN PATENT DOCUMENTS**

FIG. 1 is a perspective view of the cover plate for an electrical outlet box embodying our new design;

1462072 11/1966 France 174/66

FIG. 2 is a front elevation view thereof;

FIG. 3 is a left side elevation view thereof;

FIG. 4 is a rear elevation view thereof;

FIG. 5 is a top plan view; and,

FIG. 6 is a cross-sectional view thereof taken along line 6—6 of FIG. 2.

FIG.1

FIG.3

FIG.2

FIG.6
